UNITED STATES PATENT OFFICE.

WILLIAM J. STOOP, OF WHEELING, WEST VIRGINIA.

ARCH FOR THE FIRE BOXES OF BOILERS.

Application filed December 30, 1920. Serial No. 433,969.

To all whom it may concern:

Be it known that I, WILLIAM J. STOOP, a citizen of the United States of America, and resident of Wheeling, county of Ohio 5 and State of West Virginia, have invented certain new and useful Improvements in Arches for the Fire Boxes of Boilers, of which the following is a specification.

This invention relates broadly to fire-boxes for water-tube boilers, and more specifically to a suspended arch for such fire-boxes.

The primary object of the invention is to provide an improved arch for the fire-boxes 15 of water-tube boilers, the same being so constructed that it possesses unusual capability of resisting the deteriorating effects of the intense heat to which such arches are subjected.

20 A further object is to provide an arch having improved means whereby it is maintained in a relatively cool condition, with the end in view to greatly prolong its serviceable life.

25 A still further object is to provide, in association with such arch, improved means whereby the arch is supported in a suspended position.

With these and other important objects 30 in view, the invention resides in the features of construction, arrangement of parts and combinations of elements which will hereinafter be fully described, reference being had to the accompanying drawings, in 35 which—

Figure 1 is a longitudinal section of a fire-box embodying my invention;

Figure 2 is an enlarged section taken substantially on the line 2—2, Fig. 1, showing 40 in top plan the arch-facing;

Figure 3 is an enlarged longitudinal section of the arch, illustrating the suspension means; and—

Figure 4 is an enlarged transverse section of a fragmentary portion of the arch, said section being taken approximately on line 4—4, Fig. 3.

Referring to said drawings, in which like 50 designating characters distinguish like parts throughout the several views—

1 indicates the front wall, 2 the mud-drum, and 3 the tubes of a boiler of a more or less familiar type, said front wall having therein an opening or passage 4 through 55 which fuel is introduced into the fire-box 5. As herein shown, said passage 4 is fitted

with a gas burner 40, but it is obvious that an oil burner may be substituted for said gas burner, or that coal may be employed as fuel either alone or in conjunction with gas. 60

Overlying the fire-box 5 and supported at its outer end by the front wall 1 is an arch, designated generally by the numeral 6, which constitutes the present invention.

Said arch, which is of the type generally 65 termed flat, comprises an I-beam support

7 which is disposed transversely of the boiler setting at a suitable distance from said front wall 1 and which has attached thereto the inner ends of a plurality of relatively-spaced parallel bars 8. Said bars,

which are slightly inclined from the horizontal in an upward and inward direction, have their outer ends resting upon the top of said wall 1, or upon an angle-bar flange 75

9 carried by the inner side-wall of a main air-supply conduit 10 which surmounts said wall, as shown. The inner end portion of each of said bars 8 carries thereon, or has formed integral therewith, a hanger-lug 11 80

which seats in overlying relation to one of the bottom flanges of the I-beam 7; and a second hanger 12, detachably carried by the bar 8, seats upon the opposite bottom flange of said I-beam in opposing relation to said 85 hanger 11, said hangers cooperating with said I-beam for suspending said inner end of said bar.

Each bar 8 is, generally speaking, of I-beam form, having extending throughout 90 its length a base portion providing opposite horizontal flanges 8^a; and disposed in suspended relation to said flanges is a

plurality of parallel courses of aligned heavy blocks 13, 14 and 15 composed of a refractory material which will successfully resist 95 high temperatures. Said blocks are arranged to form an approximately horizontal flat wall which constitutes a facing for the arch adapted to be directly exposed to the 100 heat and flames resulting from combustion of the fuel within the fire-box 5.

The upper portions of the blocks 13, 14 and 15 of each course have a width approximating the distance between adjacent bars 105 8, and each of said blocks is channeled longitudinally on opposite sides to provide downwardly-facing shoulders 16 which rest upon the flanges 8^a of adjacent bars, whereby said blocks are suspended. The blocks 110 of each course have the sides of their lower body portions disposed in meeting or abut-

ting relation to those of adjacent courses, as is clearly shown in Fig. 4, to form a continuous flat arch facing. Suitable interlocking means, as rib-like lugs 17 formed 5 upon one side of the blocks of each course and received within channels 18 provided therefor in the blocks of the next adjacent course, are preferably provided.

The alined blocks 13, 14 and 15 of each 10 course are secured against relative movement by means of a tie-rod 19 directed through alined holes 20 provided therefor in said blocks, said rods having nuts 21 threaded upon their opposite ends and received in recesses 22 provided in the opposite end-blocks 15 and 15, which recesses are designed to be filled with a suitable refractory material for protecting said nuts and the ends of the rod from the intense heat to which they would 20 be subjected if exposed. As is obvious, any number of the intermediate blocks 14 required by arches of different lengths may be employed.

The blocks are designed to be cooled by a 25 constantly flowing current of cold air directed therethrough, each thereof having therein a pair of parallel air-ducts, and the ducts of adjacent alined blocks being disposed in registering relation. The outer 30 end block 13 has leading to one of its said ducts 13^a from the main air-supply conduit 10 a conducting tube 23. Air from said conduit thus passes through said tube 23 to said duct 13^a, thence through the latter to the 35 therewith registering duct 14^a of block 14, thence to the therewith registering duct 15^a of block 15. Said duct 15^a communicates adjacent to the inner end of block 15 with the parallel return duct 15^b of said block 40 through a connecting cross passage 15^c. Thus, air passes from said duct 15^a to the duct 15^b, thence to the therewith registering return duct 14^b of block 14, thence to the therewith registering return duct 13^b of said block 45 13. The said duct 13^b has its outer end curved and opening upward through the top of block 13, as shown at 24, for discharging air into the open space 25 above the course. Said open space is bounded at opposite sides by the bars 8 and is closed at its 50 top by a crown 26 composed of suitable blocks or tile which overlies the said bars and extends inward from the inner wall of said conduit 10 and terminates more or less 55 closely adjacent to the I-beam 7. Each of the overlying spaces 25 constitutes a passage through which air discharged thereto from the therewith communicating outlet 24 courses inward in contact with the tops 60 of the blocks and passes thence upward between the inner end of the crown 26 and the I-beam 7 to a chamber 27 formed in the arch 6, whence it discharges to and through a large air-duct or passage 28 leading to the breeching or to other suitable discharge 65

point. Obviously, the heated air may be conducted by said duct or passage 28 to the interior of the factory for heating the latter when such is desirable.

I-beams 29 located at a suitable distance in 70 front of and parallel to the beam 7 form supports for an upright front wall 30 and also for the outer ends of cross-beams 31 which have their opposite ends supported by said beam 7. Surmounting said cross-beams 75 31 and the beam 7 is the top wall 32 of the arch, which joins with an inner end wall 33 carried by the inner end of the arch facing and the corresponding ends of the supporting bars 8.

80 A suitable cover-plate, as 34, extends from the top of the conduit 10 to the outermost of the beams 29, as shown.

From the foregoing it will be manifest that my invention provides a simple arch and 85 arch-suspension structure for the fire-boxes of water-tube boilers, and that said structure includes an arch facing associated with air-circulating means whereby it is at all times maintained in a relatively cool condition for 90 enabling it to withstand the high temperatures generated in the fire-box.

What is claimed is—

1. An arch for the fire-boxes of boilers, comprising a plurality of relatively-spaced 95 parallel supporting bars arranged in approximately horizontal position over the fire-box, an arch facing consisting of a plurality of courses of alined blocks, each course occupying the space between adjacent bars 100 and having the blocks thereof receiving support from the latter, the blocks of each course having therein passages which communicate to form a continuous ingoing and return duct for air whereby said blocks are 105 cooled, an air-supply conduit located adjacent to the outer ends of said courses and having communication with the inlet end of the ingoing branch of each cooling duct, said cooling ducts having their discharge 110 ends opening above said courses adjacent to the rear ends of the latter, and passages for conducting air discharged from said ducts away from the arch.

2. An arch for the fire-boxes of boilers, 115 comprising a plurality of relatively-spaced parallel supporting bars arranged in approximately horizontal position over the fire-box and having their outer ends supported over the front wall of the latter, means supporting the inner ends of said bars, an arch facing suspended from said bars, said facing consisting of a plurality of courses of alined blocks, each course having the upper portions of opposite lateral edges of the blocks 120 thereof interengaged with adjacent bars and having the lower lateral edges of said blocks disposed in abutting relation to those of adjacent courses, said courses having therein 125 ducts for the passage of air whereby they 130

- are cooled, an air-supply conduit in communication with the inlet end of each of said ducts, and air passages leading from the discharge ends of said ducts to the atmosphere.
3. In an arch for the fire-boxes of boilers, relatively-spaced parallel bars, means supporting said bars in approximately horizontal position over the fire-box, an arch facing comprising a plurality of courses of blocks supported by the base portions of said bars, the blocks of each course being in alined relation and occupying the space between the base portions of adjacent bars, and the blocks of adjacent courses being in abutting relation below said bars, each course having therein connected ingoing and return ducts for the passage of air whereby they are cooled, an air-supply conduit in communication with the inlet end of each ingoing duct, a crown supported by said bars at a distance above said facing whereby intermediate passages are provided, the outlets of said return ducts opening into said passages, and means for conducting air outward from said passages.
4. In an arch for the fire-boxes of boilers, relatively spaced parallel bars, means supporting said bars in approximately horizontal position over the fire-box, an arch facing consisting of a plurality of courses of blocks supported by the base portions of said bars, the blocks of each course being in alined relation and occupying the space between the base portions of adjacent bars, and the blocks of adjacent courses being disposed in abutting relation below said bars, each of said courses having therein connected ingoing and return ducts for the passage of air whereby they are cooled, an air-supply conduit in communication with the inlet end of each ingoing duct, a crown supported by said bars at a distance above said facing whereby intermediate passages are provided, the outlets of said return ducts opening into the outer ends of said passages, an enclosed chamber over said crown, said passages opening into said chamber, and means for conducting air from said chamber.
5. In an arch for the fire-box of a boiler, a plurality of relatively-spaced parallel bars, means supporting said bars in approximately horizontal position over the fire-box, an arch facing suspended from said bars and consisting of a plurality of courses of alined blocks, each bar having opposite base flanges and the blocks of each course having their upper lateral edge portions channeled for the reception of said flanges, the blocks of adjacent courses having their lower lateral edge portions meeting beneath said bars, a crown supported above said facing whereby intermediate passages are formed, air ducts in said courses having their discharge ends opening into said passages, an air-supply conduit opening into each duct, a chamber with which said passages communicate, and air-conducting means leading from said chamber.
6. An arch for the fire-boxes of boilers, comprising a plurality of parallel relatively-spaced bars supported at their outer ends adjacent to the front wall of the fire-box, said bars occupying approximately horizontal positions, an I-beam disposed transversely adjacent to the inner ends of said bars and having said ends suspended therefrom, an arch facing suspended from said bars, said facing comprising courses of alined blocks interposed between said bars, each course having the blocks thereof interengaged at opposite sides with adjacent bars, and adjacent courses occupying meeting relation beneath said bars, each course having therein a duct for the passage of air whereby it is cooled, said ducts having their outlets located for discharging above said facing, and means supplying air to said ducts.
7. An arch for the fire-boxes of boilers, comprising a plurality of parallel relatively-spaced bars supported at their outer ends adjacent to the front wall of the fire-box, said bars occupying approximately horizontal positions, a supporting member located adjacent to the inner ends of said bars and having said inner ends suspended therefrom, an arch facing suspended from said bars, said facing comprising courses of alined blocks, each course having the blocks thereof in abutting relation to those of adjacent courses, a crown overlying said bars whereby air passages intermediate the bars are provided, an open chamber with which said passages communicate at their inner ends, each course of blocks having therein a duct for the passage of air whereby it is cooled, said ducts being arranged to discharge into the outer end portion of said passages, and means supplying air to said ducts.
- In testimony whereof, I affix my signature in presence of two subscribing witnesses.
